UNITED STATES PATENT OFFICE

2,615,654

YARN TENSIONING DEVICE

Thomas F. Suggs, Gastonia, N. C., assignor to
Cocker Machine & Foundry Company, Gastonia, N. C., a corporation of North Carolina

Application April 22, 1950, Serial No. 157,510

4 Claims. (Cl. 242—150)

1

This invention relates to yarn tensioning devices, that is to say, to devices for tensioning individual yarns or threads incident to being drawn from supply packages supported in vertical or near vertical position, as for example, in creels associated with beam warpers or the like.

The chief aim of my invention is to provide a tensioning device which, in addition to being adjustable to vary the tension on the yarn, is easily and quickly threaded, and by which excessive ballooning and attendant jerking of the yarn incident to withdrawal from the supply package is effectively prevented.

Other objects and advantages will appear from the following detailed description of the attached drawings, wherein:

Fig. 1 is a view in top plan of a yarn tensioning device conveniently embodying my invention.

Fig. 2 shows the device in side elevation.

Fig. 3 is a cross sectional view taken as indicated by the angled arrows III—III in Fig. 1; and

Fig. 4 is a broken out view drawn to a smaller scale, showing a portion of a creel equipped with yarn tensioning devices of my invention.

With more specific reference first more especially to Figs. 1-3 of these illustrations, it will be observed that my improved yarn tensioning device, there comprehensively designated by the numeral 9, comprises a flat horizontal bracket-like cast foundation or supporting member 10 which is of elongate irregular configuration in plan. At its narrow or anchorage end, the member 10 has an integrally formed upward attachment boss 11 with an upright inward web extension 12, said boss being bored longitudinally as at 13 for connection of the device to a horizontal sustaining rod 14. A set screw 15, threadedly engaged in the boss 11, serves as the means for securing the device in adjusted position along the rod 14. Fixed in the web 12, and extending forwardly therefrom at a slight elevation above the top of the member 10, is a pigtail thread guide 16 with a vertical axis eye; and formed on the wider sector-like portion 17 of the member 10 is a circular pad 18 from which upstands axially, a stud 19 whereon are freely impaled a pair of superposed yarn tensioning disks 20 and 21 of which the meeting place is on a level with the top of the eye of the pigtail guide 16. A vertically-flexible spring arm 23 is fulcrumed on the fixed post 19 and has an upstanding holder stud 25 at its

outer end for a second pair of superposed yarn tensioning disks 26, 27. The stud 25 projects below the arm 23, as at 28 in Fig. 2, so as to be selectively engageable with depressions 29 in the top surface of the member 10 radial to the fixed post 19 to maintain the arm 23 against accidental displacement in adjusted positions for a purpose later on explained. Rotation of the lower tension disks 21, 27 of the respective pairs is resisted by washers 30 and 31 of felt or the like interposed beneath them. Anchored in the member 10, at the distal end thereof beyond the tensioning disks 26, 27, is a second pigtail guide 32 with a horizontal axis eye at the level of the meeting plane of said disks.

Affixed to the bottom face of the member 10 by screws or other fastening elements 33 substantially in coaxial relation to the eye of pigtail guide 16, is a circular plate 35 of comparatively large area which serves as a baffle to prevent ballooning of the yarn as also explained later. As shown, the plate 35 has a central guide aperture 36 which is approached through a radial slot 37. Overlying the slot 37 at right angles, immediately adjacent to the aperture 36, is a tongue 38 of flat spring metal which is secured at one end to said plate 35 by one of the screws 33, and which reaches to the periphery of said plate with its distal end bent upward slightly, as at 40, to facilitate entry of the yarn therebeneath.

While serviceable in connection with other types of textile machines or apparatus, the yarn tension device of my invention in the form herein illustrated is intended for use more particularly in connection with creels of the type disclosed in U. S. Patent 2,483,160 granted to me on September 27, 1949. A portion of such creel is illustrated in Fig. 4, one of its posts 41 being shown as having secured to it at the top, a horizontal bracket 42 with vertical axis terminal bosses 43 on its oppositely extending arms to receive the upturned ends of the rods 14 by which the tensioning devices 9 of my present invention are sustained. Disposed at a level below the bracket 42 and in turn fixedly secured to the post 41 of the creel, is a horizontal bracket 45 likewise having oppositely extending but longer extremities 46. Pivoted on upstanding studs 47 on the extremities 46 of the bracket 45 are double-armed swivel elements 48 which, at their outer ends, carry holders 49 for the support of frusto-conical yarn packages 50 with the axes of the latter tilted at complementary angles toward the pivot axes of said elements.

It is to be noted that the tension devices 9 are so positioned that the apertures in the baffle plates 35 are in vertical alignment with the swivel centers of the yarn package carrier arms 48, and moreover that the prolongations of the axes of the yarn packages intersect in the apertures of said baffle plates.

The normal path of each yarn Y is as indicated in dot and dash lines in Figs. 1 and 2, i.e., upward from the package 50 and through the apertures of the baffle plate 35 of the corresponding tension device 9, then through the eye of the pigtail guide 16 for direction horizontally about the post 25 and between the disks 26, 27, then about the stud 19 and between the disks 20 and 21, and finally forward horizontally through the eye of the pigtail guide 32. Counterclockwise adjustment of the arm 23 will obviously result in increase in the drag imposed on the yarn, while clockwise adjustment will result in easement of the drag. If desired, the yarn Y may be passed directly to the disks 20, 21 from the pigtail guide 16 with consequent further decrease in the tension imposed. Due to the location of the baffle plate 35 and by virtue of its relatively large area, ballooning of the yarn is effectively minimized and controlled, with avoidance of jerking to prevent smooth running of the yarn through the guide aperture 36 in said plate. In threading, the end of the yarn is picked up from the package 50, engaged into the slot of the baffle plate 35 as shown in full lines in Figs. 1 and 2, and passed under the tongue 37 by which latter it is led to the aperture 36 in the plate 35, then entered by a rotary movement into the eye of the pigtail 16, then passed beneath the disks 26, 27 and 20, 21, and finally engaged by another rotary movement in the eye of pigtail guide 32. One hand only is thus required in the threading without necessitating release of the yarn end at any time. Accordingly this operation is not only easy, but very quick of accomplishment as will be readily understood.

As an alternative construction, the plate 35 may be made as an integrally cast portion of the foundation member 10 instead of being separately formed and attached as herein shown by way of example.

Having thus described my invention, I claim:

1. In a yarn tensioning device, a horizontal bracket; fixed vertical and horizontal axis yarn

guide eyes at the top of the plate respectively adjacent opposite ends thereof, a horizontally-arranged circular baffle plate portion at the bottom of the bracket in alignment with the vertical axis 5 guide eye having a central thread aperture approached through a radial slot; a pair of superposed tension disks free to rotate about a post upstanding from the bracket at an intermediate point offset laterally from a vertical plane containing the two guide eyes; an arm fulcrumed about the post beneath the disks and reaching into the interval between the guide eyes; a second pair of freely rotatable superposed tension disks carried at the distal end of the arm; and 10 means for holding the arm set in selectively different adjusted positions about said post.

2. A yarn tensioning device according to claim 1, wherein the two yarn guide eyes are of the quick threading pig-tail type.

3. A yarn tensioning device according to claim 1, further including a flexible guard tongue transversely overlying the slot of the baffle plate at the top adjacent the notch central aperture to retain the yarn in said aperture.

4. A yarn tensioning device according to claim 1, wherein the arm is of spring material, and wherein the holding means comprises a pendent projection at the distal end of the arm adapted to engage with indentations circumferentially spaced about the post.

THOMAS F. SUGGS.
